UNITED STATES PATENT OFFICE.

GRIFFITH D. ROBERTS, OF COLUMBUS, WISCONSIN.

PNEUMATIC HAMMER.

1,037,323.

Specification of Letters Patent. Patented Sept. 3, 1912.

Application filed July 25, 1911. Serial No. 640,506.

To all whom it may concern:

Be it known that I, GRIFFITH D. ROBERTS, a citizen of the United States, residing at Columbus, in the county of Columbia and 5 State of Wisconsin, have invented a new and useful Improvement in Pneumatic Hammers, of which the following is a specification.

My invention relates to a class of pneumatic hammers, propelled by power and used for forging metals and the object of 10 my invention is to provide a means for raising the hammer to the top of its stroke preparatory to starting on a new piece of 15 work.

My invention relates more particularly to a pneumatic hammer invented and patented by me in Patent Number 989051.

In the accompanying drawings wherein 20 like reference characters refer to corresponding parts throughout the several views—Figures 1 and 2 illustrate my invention as viewed from opposite sides. Fig. 3 is a front view of my invention.

A represents the frame of the hammer to which is attached the belt pulley B, the 25 crank shaft C and the pitman D, carrying the upper piston rod E. To the frame A is also attached the air cylinder F in which 30 are the upper or power piston E' attached to piston rod V and the lower or hammer piston V' attached to piston rod V. Between the two pistons is located the reciprocating air controlling valve G, provided 35 with an opening to the air at *g* Fig. 1. A spring, R, holds the valve stem G' in outermost position as shown in Figs. 1 and 2. In this position the valve G is open. The 40 lever H has a movable bearing K and has attached to its lower end a pawl L engaging in corrugations on the hammer T. The lever H has intermediate its ends a slanting 45 slot K that permits a rocking motion of the upper end, when the bearing K is lowered a little but when lowered farther the upper end resting on the valve stem G permits the withdrawal of the pawl Q.

The slide I engages the outer end of pawl L at its lower end and at its upper end is 50 wedge shaped, Fig. 2, so that as it descends it closes the air valve. The slide I is also wedge shaped near the lower end, Fig. 2, to gradually withdraw pawl L when depressed.

The pawls L and Q are pressed toward

the hammer rod by springs S S', Figs. 1 55 and 2. The pawl L, Fig. 2, is made strong and the ratchet teeth on the hammer rod T are made coarse to resist the downward pressure of the hammer rod when engaged and the upper piston working. The pawl Q 60 has its end rounded to engage with corrugations on the hammer rod in any position whether the pawl L is engaged or not when the pressure on the hammer is light.

The slides H and I are carried up and 65 down by the arms M M sliding in lugs N N on the frame. The arms M M are held up by springs O O and are pulled down by rods P P connected with a pedal W at the base of the frame. 70

It is operated as follows: Pressure on the foot lever pulls downward the arms M M and the slide I acts to close the air valve G. The upper reciprocating piston exerts an alternating pressure and suction on the 75 lower piston. The lower or hammer piston is held from descending by pawl L, controlled by slide I, and by pawl Q controlled by lever H. In this situation every stroke of the upper piston lifts the hammer piston 80 a little and the latter is held from descending by pawls L and Q until it has reached the top of the stroke. Further pressure on the pedal forces the air valve farther shut and releases the pawls L and Q permitting 85 free action of the hammer piston. By this device when the pedal pressure is nearly off, if the hammer is down it will be gradually raised to the top, or if it be stopped with the hammer down the first pressure on the pedal 90 gradually raises it.

I am aware that pneumatic hammers controlled by lever and foot power have been made before, but—

What I do claim and desire to secure by 95 Letters Patent is—

In a pneumatic hammer, a supporting frame, a cylinder supported by said frame, upper and lower pistons in said cylinder, the lower cylinder having a hammer rod, 100 said hammer rod having a series of rounded corrugations and a series of ratchet teeth at its lower end, a reciprocating valve and stem, a pair of spring pressed pawls, one of said pawls normally engaging said rounded corrugations and the other engaging said ratchet teeth, a slide having oppositely 105 beveled ends, engaging said valve stem at

its upper end and engaging at its lower end the pawl which engages said ratchet teeth, a lever engaging at its upper end with said valve stem and at its lower end 5 being connected to the pawl engaging said rounded corrugations, a lever having a slanting slot, an arm having one end

loosely mounted in said slot, a second arm pivoted to said slide, and means for reciprocating said arms.
